UNITED STATES PATENT OFFICE.

CORNELIA M. POST, OF LANGHORNE, PENNSYLVANIA, ASSIGNOR TO THE AMERICAN LINOLEUM MANUFACTURING COMPANY, OF NEW YORK, N. Y., A CORPORATION OF NEW YORK.

DESIGN FOR LINOLEUM FLOOR COVERING.

Application filed December 10, 1924. Serial No. 11,637. Term of patent 7 years.

To all whom it may concern:

Be it known that I, CORNELIA M. Post, a citizen of the United States, residing at Langhorne, in the county of Bucks and State of Pennsylvania, have invented a new, original, and ornamental Design for Linoleum Floor Covering, of which the following is a specification, reference being had to the accompanying drawing, forming a part thereof, and in which is presented a plan view of a portion of a floor covering embodying my design, said portion showing the design which is repeated throughout the covering.

I claim:

The ornamental design for linoleum floor covering, as shown.
